UNITED STATES PATENT OFFICE.

SAMUEL G. SUPPLEE, OF NEW YORK, N. Y.

DENTURE.

957,913.

Specification of Letters Patent. Patented May 17, 1910.

Application filed December 12, 1907. Serial No. 406,156.

To all whom it may concern:

Be it known that I, SAMUEL G. SUPPLEE, a citizen of the United States, residing at the city, county, and State of New York, 5 have invented certain new and useful Improvements in Dentures, of which the following is a full, clear, and exact description.

My invention relates to improvements in dentures, and particularly to what I will 10 term a bar plate, in which the two spaced apart sections of the plate are connected in a unique and most effective manner.

The object of the invention is to provide in a denture of this character a construction 15 which will give the greatest strength with the least possible weight and material, and to provide a plate which may be worn with great comfort and ease, the bar portion of the same being self-cleansing, thereby doing 20 away with the danger of irritation. The construction is also such that there are no corners or edges presented to cause irritation.

In the drawings Figure 1 is a front perspective of a bar-plate of my improved construction in one form. Fig. 2 represents conventionally the lower gum and ridge with several natural front teeth therein. Fig. 3 is a view from the inner side of the 30 plate as it appears when in place. Fig. 4 is a side elevation partly in section of a detail. Fig. 5 is an end elevation partly in section of Fig. 4.

1—1 represent the two spaced-apart, side- 35 sections of a lower plate having certain artificial teeth 2—2 carried thereby in the usual manner.

3—3 are clips or clasps, so-called, which are preferably provided at the forward 40 edges of the two side members 1—1, the same being adapted to coact with suitable anchorage teeth or crowns in the mouth.

4—4^a are connecting bars of round or substantially round cross section and preferably tubular or hollow. The bar 4 is arranged to lie inside, while the bar 4^a is arranged to lie outside of the ridge of the 45 gum when the plate is in place.

In Fig. 2, 5 conventionally represents the 50 gum, 6—6^a are natural teeth therein, 7—7 crown teeth, the latter furnishing an anchorage for the clasps 3—3. When the plate is in place, the clips pass over the anchorage teeth 7—7 in the usual manner and

steady the plate, while the bars 4—4^a firmly 55 hold the two sections of the plate against all danger of displacement, thus insuring safety and absolute comfort. By making the bars tubular or hollow, greater strength and rigidity is afforded, and by making 60 them round or oval in cross section, or substantially so, they resist strains in all directions equally well. Even should either bar touch the gum, no dangerous pocket is formed in which food can become lodged 65 to the discomfort of the wearer and the irritation of the tissues, because, as will be seen, the point of contact with the gum can only be on a very narrow line. I preferably, however, so arrange and design the plate 70 that there is a slight space between each of the bars and the gum.

The plate members 1—1 may be formed of rubber or gold, or may be composite with a gold base and a rubber exposed surface. 75 The ends of the bars 4—4^a may be secured to the downwardly extending flanges of the plate sections 1—1 in any desired manner, as by flattening the ends and soldering, vulcanizing, or otherwise attaching the same 80 to the respective plate flanges. In the preferred form, the clasps 3 and bar 4 are secured as shown in Figs. 4 and 5. The clasp 3 is provided with a pin 3^a extending into the body portion of the plate-member 1. 85 The end of the bar 4 is flattened and the flattened portion 4^b is bent upward and hooked over the crown of the under surface of the plate-member 1 and is secured to the pin 3^a by soldering or otherwise attaching the 90 parts together and not only more firmly secures the clasp to the plate-member 1 but also firmly anchors the ends of the bar 4.

In Fig. 3 I have shown the plate as it would appear in place and viewed from the 95 inside. In some instances only one connecting bar may be employed, preferably the inner bar 4 which extends around the lingual surface of and below the neck of the teeth, which, because of its round cross section, possesses all of the aforesaid advantages, including a uniform resistance to strains in every direction, thus materially relieving the abutment teeth which now serve merely as a means to keep the plate properly seated. 100 105

What I claim is:

In a denture, two saddles bearing artificial teeth and arranged to be removably an-

chored to two abutments on opposite sides of the lower jaw, a round bar shaped to the contour of the inner side of the arch of the lower jaw and arranged when in place 5 slightly away from the gum tissues and below the margin of the gum, and including metallic abutment engaging clips, said

metallic bar being directly connected to said metallic clips.

SAML. G. SUPPLEE.
